UNITED STATES PATENT OFFICE.

F. ROBERT SEIDENSTICKER, OF WEST MERIDEN, CONN., ASSIGNOR TO BRADLEY & HUBBARD MANUFACTURING COMPANY, OF SAME PLACE.

DESIGN FOR A CHANDELIER.

SPECIFICATION forming part of Design No. 11,942, dated August 10, 1880.

Application filed July 2, 1880. Term of patent 7 years.

To all whom it may concern:

Be it known that I, F. ROBERT SEIDENSTICKER, of West Meriden, in the county of New Haven and State of Connecticut, have 5 invented a new Design for Chandeliers; and I do hereby declare the following, when taken in connection with the accompanying drawings and the letters of reference marked thereon, to be a full, clear, and exact description of 10 the same, and which said drawings constitute part of this specification, and represent, in—

Figure 1, a front view; Fig. 2, view of the canopy, looking upward.

This invention relates to a design for fixtures for gas or for supply lamps; and it consists in the configuration and ornamentation, as shown in the accompanying illustrations, and hereinafter described.

B, the arm, which is straight and horizontal, 20 is represented as supported by diagonal brace C from the central rod below, and also a diagonal brace, D, above, running from the arm up to a base, E, on the central rod. The upper braces are ornamented by a series of points on 25 their upper side, as shown.

At the burner end is represented a brace, F, as extending down and outward to the lower end of the burner-support.

The space between the braces is filled by a circle, H, with arms extending up and down 30 and to the right and left, as shown in the accompanying illustration.

The arms may be used as a bracket, and therefore the invention is not to be limited to the presence of the central rod. 35

The canopy L is in form of an inverted cone, its edge scalloped and surface ornamented by a series of points near the edge, and with quarto foils below with intermediate circumferential grooves, as shown. 40

I claim—

1. The design for chandelier, consisting of the arm B, with the braces C, F, and D, the brace D ornamented by a series of points, as shown in the accompanying illustrations. 45

2. The design for canopy for chandelier, consisting of the conical shape, with the edge scalloped, a series of points near the edge, with quarto-foil and circumferential grooves, as shown in the accompanying illustrations. 50

F. ROBERT SEIDENSTICKER.
